UNITED STATES PATENT OFFICE.

RAYMOND HENRY, OF ROCK ISLAND, AND WARREN M. MANSFIELD, OF MOLINE, ILLINOIS, ASSIGNORS, BY MESNE ASSIGNMENTS, TO MOLINE PLOW COMPANY, INCORPORATED, OF MOLINE, ILLINOIS, A CORPORATION OF VIRGINIA.

METHOD OF MAKING FORGED TRACTOR GEARS.

Application filed March 16, 1921. Serial No. 452,749.

To all whom it may concern:

Be it known that RAYMOND HENRY and WARREN M. MANSFIELD, citizens of the United States, residing at Rock Island, county of Rock Island, State of Illinois, respectively, have invented certain new and useful Improvements in Methods of Making Forged Tractor Gears, of which 10 the following is a specification.

The invention relates to gears and methods of making the same.

It is particularly concerned with the construction of and the method of making tractor driving gears.

The large driving gears on the drive wheels of a tractor, sometimes called "bull gears," are subjected to very severe strains because they transmit all the driving torque 20 exerted on the tractor wheels and are subjected to excessive wear owing to the fact that tractors usually operate through dust and dirt. The gears must be hard to withstand the wearing action, but should be malleable to withstand the shocks and stresses 25 to which they are subjected. Gears of cast iron and cast steel have been employed but have not proven satisfactory. The gears either break too easily, or wear out too 30 quickly.

The present invention has been devised to overcome these objections and to provide a strong durable inexpensive bull gear that will withstand the wear as well as the 35 stresses to which it is subjected.

This general object is accomplished by a drop forging process in which various gear parts are forged and subsequently assembled, thereby producing a gear having the 40 strength, hardness and rigidity of a solid forged gear by a process which does not require the expensive tools, expensive processes or the expensive material that would be necessary if the gear were forged as a 45 solid one-piece gear.

An embodiment of the invention is illustrated in the accompanying drawings and the process is explained in the specification and illustrated in the drawings.

50 Figure 1 illustrates a piece of metal stock out of which a portion of the gear may be forged.

Figure 2 shows the general shape of the

metal stock after it has been shaped in the first operation. 55

Figure 3 shows the shape of the piece in Figure 2 after another operation.

Figures 4 and 5 show the piece after still another operation.

Figure 6 shows the assembled gear. 60

The metal stock out of which the gear is made is preferably in the form of a round bar 1, such as illustrated in Figure 1. This bar is cut to the proper length and heated to a forging temperature. 65

The heated bar is then bent or shaped on the edge of a blocking die or "edger" and placed in an impression in the blocking die and worked back and forth between this impression and the "edger" until the bar takes 70 the shape and form shown in Figure 2. The exact shape of the different portions of this piece may be varied to suit the requirements, the general principle followed being that the metal is thickened at certain places and 75 thinned at others so that when it is placed in the blocking and finishing dies, there will be the proper amount of metal at the proper place to make a completely filled out finished piece. A tong hold 2 is left at one end so 80 that the piece may be easily handled.

The crudely shaped metal stock is then reheated, if it has not retained a sufficient amount of heat to continue the forging process, and put in a finishing die where it is 85 forged to the finished shape shown in Figure 3. This forging operation is continued until the die is filled and the die faces strike one another indicating that the piece is 90 finished.

The gear section as forged in the finishing dies takes accurate shape with a peripheral portion 4, a radial portion 5 and a hub portion 6. Conical projections 7, 8 and 9 and tapered holes 11, 12 and 13 are formed during this operation. 95

During the finishing operation, the excess metal is forced out and forms a rough edge 10 called the "flash." The forging is taken from the finishing dies to trimming dies 100 where this "flash" is trimmed off leaving a completed forged gear section, such as illustrated in Figure 4.

This finished section forms one sixth of a complete gear, although, of course, the exact number of sections can be varied as re- 105

quired. It will be observed that the projections 7, 8 and 9 are complementary to the holes 11, 12 and 13 respectively. For example, referring to Figure 4, if a second section exactly like that shown in Figure 4 were fitted on to the one illustrated in that figure, the hole 11 would fit over the conical projection 7 and the holes 12 and 13 would fit over the conical projections 8 and 9. It will be observed that the taper of the holes is opposite to that of the taper of the projections so that when the projections extend through the holes and are riveted, as will be later described, the parts are firmly locked together. Another important feature is that the hub portions overlap for nearly one-half their length, thereby reinforcing each other when the gear is assembled.

After the gear section is forged to its completed shape, it is placed in the die of an assembling press and as soon as a succeeding section is completed, that section is also placed in the die with the conical projections of one section inserted through the complementary tapered holes in the other section. The forging operations and the assembling of the forged pieces in the assembling die are carried out rapidly so as to prevent the pieces from becoming too cold, but in case they should become cold in the assembling press, means is provided for keeping the projections on the gear sections heated to a temperature that will permit them to be riveted.

After a sufficient number of gear sections have been placed in the assembling dies to make a complete gear, the dies are closed and the ends of the conical projections are riveted over to hold all the sections rigidly together.

When removed from the assembling press, the gear is, in effect, a rigid forged gear. It is then machined in the same manner as if it were a one piece gear, that is, it is turned to the proper diameter and teeth are cut in its periphery.

This process of making gears makes it possible to use standard stock materials; to use relatively small forging hammers and dies, and it results in very little waste. If a large gear were to be forged as a unit, the size of the hammers and dies would be prohibitive, the cost of the large pieces of stock would be high, and there would be excessive waste in the various parts that would have to be cut out of the block.

It is possible to obtain on the market, in the form of bars, a variety of the best gear steels. It is therefore possible with the process herein described, to select and carry in stock, at relatively small expense, a range of materials from which gears can be made to suit varying requirements. If stock in the form of large pieces were necessary

such as if the gear were forged as a unit, it would not be as easy to get a wide range of materials and the cost would be prohibitive.

The process itself is relatively simple and inexpensive, since only a few simple forging operations are required. The gear sections are duplicates of one another which simplifies the assembling operation since the operators do not have to use special care to see that special parts are fitted in at the right place.

The gear that results from this process is both strong and durable. It is strong because each section is strong, these sections are interlocked at both the periphery and the hub portions, and the sections are tightly riveted together with rivets that are of liberal size and a portion of one of the pieces. It is durable because made of selected material that is subjected to forging operations.

The subject matter relating to the gear, as distinguished from the process of making it, has been made the subject matter of divisional application Serial No. 636,360, filed May 3rd, 1923.

It is to be understood that the process described may be varied in some respects and that the construction shown may be varied without departing from the spirit and scope of the invention as defined by the appended claims.

1. The method of making a forged gear having more than two spokes which comprises forging a spoke with a hub portion on one end and a peripheral or rim portion on the other, assembling a plurality of said sections of sufficient number to make a complete gear, and fastening the sections together.

2. The process of making a forged gear having more than two spokes which comprises forging a spoke with a hub portion on one end and a peripheral or rim portion on the other end, the hub and rim portions being shaped so that when the parts are assembled, adjacent portions will partially overlap one another, assembling a plurality of the forged sections into a complete gear, and fastening the overlapping portions together.

3. The method of making a large forged gear which consists in bending a metal rod into the approximate shape of a gear section, forging the shaped part into a gear section, assembling a plurality of forged sections into a complete gear and fastening the sections together.

4. The method of making a large forged gear which consists in forging a piece of metal into the shape of a gear section with a peripheral portion, a radial or spoke portion, and a hub portion, and with projections and holes complementary to holes and

projections of an adjacent gear section, assembling a plurality of the sections together with the projections of one extending through the holes of the other, and riveting the projections to unite the sections into a complete forged gear.

5. The method of making a large forged gear which consists in forging a metal rod into the shape of a gear section with a 10 peripheral portion, a radial or spoke por-

tion, and a hub portion, assembling a plurality of said sections together with the peripheral and hub portions of one section overlapping the peripheral and hub sections of the other portion and fastening the sections together.

In testimony whereof, we affix our signatures.

RAYMOND HENRY.

WARREN M. MANSFIELD.
